DESIGN FOR A MIRROR

James J. Connors, Meriden, Conn., assignor to
The Charles Parker Company, Meriden, Conn.,
a corporation of Connecticut

Application November 5, 1936, Serial No. 65,698

Term of patent 3½ years

To all whom it may concern:

Be it known that I, James J. Connors, a citizen of the United States, residing at Meriden, in the county of New Haven and State of Connecticut, have invented a new, original, and ornamental Design for a Mirror, of which the following is a specification, reference being had to the accompanying drawing, forming part thereof.

Fig. 1 is a view in front elevation of a mirror showing my new design;

Fig. 2 is a side view thereof; and

Fig. 3 is a top view thereof.

My design is characterized by a rectangular frame enclosing a mirror flanked upon its op-

posite vertical edges by corresponding, parallel, vertical pilasters extending nearly to the upper and lower edges of the frame and equally offsetting from the plane of the mirror and provided at their upper and lower ends with corresponding horizontal caps offsetting from the plane of the frame and substantially equally spaced from the horizontal upper and lower edges thereof.

I claim:

The ornamental design for a mirror as shown and described.

JAMES J. CONNORS.
